Atlys.

UNITED STATES PATENT OFFICE.

HERBERT W. DAY, OF WOLLASTON, MASSACHUSETTS, ASSIGNOR TO PAINTING & FINISHING EQUIPMENT SALES CO., A CORPORATION OF MASSACHUSETTS.

APPARATUS FOR APPLYING COATING.

Application filed March 1, 1922. Serial No. 540,171.

To all whom it may concern:

Be it known that I, HERBERT W. DAY, a citizen of the United States, and a resident of Wollaston, in the county of Norfolk and

5 State of Massachusetts, have invented an Improvement in Apparatus for Applying Coating, of which the following description, in connection with the accompanying drawings, is a specification, like characters on the 10 drawings representing like parts.

This invention relates to apparatus for applying coating to surfaces.

The coating, if a liquid, may be a paint japan, varnish of any other suitable coating medium, or it may, if desired, be a solid in powdered form, and the material or surface to which it is to be applied may be of any character, such, for example, as wood, metal or other material.

20 Referring more particularly to the drawings, wherein I have represented a single embodiment of my invention,—

Fig. 1 is a vertical longitudinal section of a tool constructed in accordance with my 25 invention;

Fig. 2 is an end elevation of the tool looking toward the right in Fig. 1;

Fig. 3 is a vertical section upon the line 3—3 of Fig. 1;

30 Fig. 4 is a similar section but representing the supplementally air discharging member as turned to a position ninety degrees removed from that indicated in Fig. 3; and

Fig. 5 is a vertical central section of the 35 discharge end of the tool but representing a somewhat modified form of my invention.

The tool or appliance may be of any suitable material but is preferably metallic and may be of the general form shown in my

40 Patent No. 1,172,233, dated February 15, 1916, or of any other suitable form or construction. The body 1 is, however, preferably provided with a handle or extension

45 2 integral therewith and provided with a guard 3 inclosing the free end of the valve operating lever 4 pivoted at 5 upon the body 1. In the disclosed form of the invention, the said operating lever 4 is of general trigger form, but such construction may be widely varied within the scope and purpose of the invention.

50 The handle 2 is provided with a passage 6 for the paint or other suitable coating liquid or powder, which may be supplied through gravity or under suitable pressure

if desired and also with a passage 7 for the air or other suitable fluid under pressure. In the form of tool herein shown, I have represented the passages 6, 7 as pipes suitably secured in the body 1 and as communicating at their inner ends with passages 8, 9 cored or otherwise suitably provided in the body 1. Controlling the paint supply passage 8 is a valve which may be of any suitable form, but which is herein represented as an axially movable piston or plunger 10 positioned within a valve casing 11 and having a stem 12 extending through the valve casing into contact with the operating lever 4, as clearly shown in Fig. 1. The valve here shown as a piston or plunger is normally held seated by a coiled spring 13 surrounding the stem 12 and seated in a recess 14 in a cap 15 threaded at 16 into the body 1 similarly threaded at 17.

The passage 9 for the air is controlled by a similar valve indicated generally at 18 in Fig. 2, the spindle 19 thereof contacting with the valve operating lever 4 which is shaped so as to engage both valves in a manner herein unnecessary more fully to illustrate.

The body 1 is cored to provide a longitudinal passage 20 which is internally threaded at 21, 22 for the reception respectively of a tubular member 23 threaded at 24 and a needle valve 25 threaded at 26. The tubular member 23 at its forward end is preferably suitably formed to permit the passage of the coating material issuing from the valve chamber 10 into the passage 27 and thence into the circumferential space 28. For this purpose, the forward end of the tubular member 20 is preferably squared. Thus the coating material, when the valve 10 is opened, is permitted to flow through the passage 6, the valve casing 11, the passages 27, 28, and thence past the squared formation. Upon the forward end of the tubular member 20 is threaded or otherwise positioned a cap 30, which may if desired be similar to the corresponding member in my Patent No. 1,172,233. The needle valve 25 is seated at its outer end in the cap 30 as indicated in Fig. 1, and the forward end of the said needle valve is guided and positioned by any suitable means, as, for example, by a coiled wire 31 encircling the head of the valve and maintaining it in a

central position when the valve is unseated. The rear end of the valve 25 may be provided with a suitable lock nut 32.

The air passage 9 is in communication 5 with a passage 33 indicated in dotted lines in Fig. 1, which is itself in communication with the valve chamber containing the valve 18 and extending from such valve chamber 10 is an air passage 34 indicated in dotted lines in Fig. 1 and communicating with a passage 35 forming an enlargement of the passage 36 of the tubular member 20. When the valve 18 is opened, the air flows through the passage 33 past the valve 18 through the 15 passages 34, 35 and into the passage 36 governed or controlled by the needle valve 25.

Upon the outer end of the body 1 is threaded or otherwise suitably secured a 20 preferably cap-like member 37 herein shown as having a concaved or curved inner surface 38 and a small central opening 39 in line with the axis of the needle valve 25. The length of the threaded portion 40 of the cap-like member 37 is sufficient to permit 25 adjustment of the member 37 so as to provide for the effective formation of a film and the variation of the thickness thereof as described in my Patent No. 1,172,233. Such film is constantly formed and maintained by capillary action between the 30 surface 38 and the outer surface 41 of the inner cap 30 which are brought close enough together to insure such action. The air entering through the passage 36 breaks through 35 the film at the central portion of the cap and discharges the same upon the work in very fine globules. Said film is constantly broken by the air or other fluid but is constantly restored through the action of capillarity. Hence the coating material may be 40 merely under suction due to capillary action. The maintenance of the supply of coating material is not dependent upon the presence of the air current which is used 45 merely to break the film and discharge the globules. I effect through the described construction a very fine division of the coating material as set forth in my said Patent No. 1,172,233.

The construction of parts thus far described effects the formation of a mass of spray of general conical form issuing through the orifice 39, but generally circular in cross section. This result is effected by 50 the disruption of the film formed between the cap-like members 30, 37 through the agency of the air or other suitable fluid in the manner already described.

I am aware that it has been proposed to 55 modify the character of the spray issuing from a tool or appliance for applying coating by means of supplemental jets of air directed upon the discharged spray, as shown, for example, in the patent to Bur- 60 dick, No. 649,430, dated May 15, 1900. In

accordance with this patent, the shape of the spray discharge is changed from a circular form into that of a thin sheet through the use of supplemental air jets directed upon the spray issuing from the discharge 70 end of the tool or like appliance.

As fully set forth in my Patent 1,321,014, I therein provide for discharging supplemental air jets upon the discharged film of paint or other coating material and in such 75 a manner as to change or transform the issuing spray from a conical formation circular in cross section into a sheet. In said patent I disclose means and a process whereby a mass of spray as discharged may be 80 given any form in cross section between that of a relatively thin sheet and a cone or mass circular in cross section.

In accordance with the present invention I provide means whereby the issuing spray 85 may be permitted to retain its shape defined as circular in cross section or whereby said issuing spray may be given the form of a relatively thin sheet located or existing in any one of a plurality of lines or planes. In 90 the disclosed embodiment of the invention means are provided to give the issuing spray the form of a relatively thin sheet in either of two lines or planes 180 degrees apart, but within the scope and purpose of the invention, other and intermediately positioned lines or planes of discharge may be provided for. Without limiting myself to the disclosed embodiment, I will set forth one 95 means for accomplishing the desired result. 100

I provide a generally cylindrical member 42 having any suitable number of (and preferably two) tubular extensions 43, 44, preferably diametrically opposed to each other and terminating in discharge passages 45, 105 46 desirably inclined toward each other and clearly represented in Fig. 1.

The two or other number of supplemental air passages 43, 44 are in communication at certain times at their inner ends through 110 ports or passages 47, 48, with a completely annular passage or groove 49 formed upon the outer surface of the forward end of the body 1 as indicated in Fig. 1, said annular passage or groove communicating with the 115 ports or passages 47, 48 through four ports or passages 50, 51, 52, 53, most clearly indicated in Fig. 3, it being understood that more than four ports or passages may be provided, thus giving still further positions 120 of the coating sheet.

Each of the ports or passages 47, 48 is preferably of small diameter, and the several passages 50, 51, 52, 53, are also of small diameter, so that by a relatively slight turning movement of the cylindrical member 42, the passages 47, 48 are removed from communication with the ports or passages 50, 51 or 52, 53, as the case may be. 125

In that form of my invention shown in 130 Fig. 1 the cylindrical member 42 is pro-

vided with a relatively long threaded inner surface 54 that engages a similar threaded surface 55 upon the body 1. Within the scope of my invention I may in this manner 5 provide for longitudinal adjustment of the cylindrical member without interfering with the communication between the port or passages 47, 48 and the annular passage 49, by making the several passages of the proper 10 size, but desirably the passages are of such size that a comparatively small movement of the cylindrical member 42 in a circumferential direction interrupts the communication. The threads 54, 55 are of such character 15 that a sufficient turning movement to cause engagement or disengagement of the said ports and passages will not cause leakage of the air or other motive agent between the threads.

20 The annular passage or groove 49 and hence the passages 43, 44 are in communication with the longitudinally extending passage 56 and the communicating passage 57 of the body 1, such passage 57 being in 25 communication with the main air passage 35 through a small port 58. Said port 58 is not controlled by a valve as in my said Patents 1,321,014 and 1,368,612, since in 30 order to interrupt the communication between the main air passage 35 and the supplemental air passages 43, 44. I depend wholly upon the described turning movement of the cylindrical member 42.

It will be evident that the annular passage 35 or groove 49 may if desired be formed in the inner surface of the member 42 and that other changes may be made within the scope and purpose of my invention. It will be understood from the foregoing description 40 that the supplemental air passages 43, 44 are not in constant communication with the annular passage or groove 49, but are in communication therewith only in certain circumferential positions, which in the disclosed embodiment 45 of the invention are located ninety degrees apart, so that the coating or paint sheet, in the disclosed embodiment of the invention would exist either in the plane of the sheet of the drawing or in a plane normal thereto, it being understood that by increasing 50 the number of ports or passages, intermediate communicating positions may be provided for. With the present disclosure, however, the passages 43, 44 are out of communication 55 with the annular passage 49 at all positions excepting the two that I have described.

In Fig. 5 I have shown a slightly modified form of my invention wherein the cylindrical member indicated at 42' is of shorter length but is desirably screw threaded as indicated at 59 upon its inner surface. Upon the body 1 in the rear of the said cylindrical member 42' is a nut 60 serving to lock or hold the cylindrical member 42' in any

position into which it may be turned. Otherwise the construction shown in Fig. 5 is desirably the same as that shown in Fig. 1.

My invention in its broadest application 70 is not limited to the formation of a film of the coating material, since such coating material may be positioned with respect to the discharging motive fluid in any suitable manner. Preferably, however, I provide 75 for forming, breaking through and discharging the film.

Having thus described one illustrative embodiment of my invention I desire it to be understood that although specific terms are 80 employed they are used in a generic and descriptive sense and not for purposes of limitation, the scope of the invention being set forth is the following claims.

Claims—

1. Means for applying coating comprising means to supply coating material, means to subject the same to the action of a motive agent, thereby effecting the discharge of the coating material, and means to discharge a motive agent supplementally upon the discharged coating material in any one of a plurality of predeterminedly spaced planes, the control of the discharge of the motive agent supplementally being effected 90 wholly by change in position of the means to discharge the motive agent supplementally said change in position cutting off the supplemental discharge when not in said predeterminedly spaced planes. 100

2. Means for applying coating comprising means to supply coating material, means to subject the same to the action of a motive agent, thereby effecting the discharge of the coating material, and a member 105 through which the motive agent may be discharged supplementally upon the discharged coating material, said member having a plurality of predeterminedly spaced positions in each of which the motive agent is supplementally discharged thereby, and one or more intermediate predetermined positions in which no supplemental discharge of the motive agent occurs. 110

3. Means for applying coating comprising 115 means to supply coating material, means to subject the same to the action of a motive agent, thereby effecting the discharge of the coating material, and a member through which the motive agent may be discharged supplementally upon the discharged coating material, said member being mounted for turning movement upon the coating applying means, and having a plurality of predeterminedly spaced positions in each of which the motive agent is supplementally discharged and one or more intermediate predetermined positions in each of which the discharge of the motive agent supplementally is prevented. 120 125 130

4. Means for applying coating comprising means to supply coating material, means to subject the same to the action of a motive agent, thereby effecting the discharge of the coating material, and a member through which the motive agent may be discharged supplementally upon the discharged coating material, said member having opposed supplemental discharge passages adapted to occupy discharging positions in two planes or lines which are substantially normal to each other, and to occupy intermediate positions in which the supplemental discharge is prevented by reason of such positioning of said member.
5. Means for applying coating comprising a body having means for maintaining a film of coating material and also having means for causing a motive agent to break through and discharge said film, and a member adapted to discharge the motive agent supplementally upon the discharged film to transform the latter into a mass having a different cross section, said member being mounted for rotation upon said body and adapted supplementally to discharge the motive agent only in a plurality of predeterminedly spaced planes, the control of the discharge of the motive agent supplementally in said planes being effected wholly by change in rotational position of the said member upon said body.
6. Means for applying coating comprising means for maintaining a film of coating material, means for causing a motive agent to break through and discharge said film, and means to discharge the motive agent supplementally upon the discharged film to transform the latter into a mass having a different cross section, the means to discharge the motive agent supplementally upon the discharged film having a plurality of predeterminedly spaced positions in each of which the motive agent is supplementally discharged thereby and intermediate predetermined positions in which no supplemental discharge of the motive agent occurs.
7. A tool for applying coating comprising a body having passages for coating material and for a motive agent under pressure there being in said body a plurality of pairs of spaced, supplemental, motive passages leading from said motive agent passage and distributed in a circular series thereabout and a member supported upon said body and having a pair of opposed supplemental mo-
- tive agent discharge passages, said member having turning movement, without necessary substantial longitudinal movement, upon said body into and out of communication with selected supplemental motive passages.
8. A tool for applying coating comprising a body having passages for coating material and for a motive agent under pressure and a member supported for turning movement upon said body and having two opposed supplemental motive agent discharge passages, said member having two motive agent passages leading to the said discharge passages and said body having a number of spaced supplemental motive agent passages constituting a multiple of two, and respectively in communication with the motive agent supply.
9. A tool for applying coating comprising a body having passages for coating material and for a motive agent under pressure and a member supported for turning movement upon said body and having two opposed supplemental motive agent discharge passages, said member having two motive agent passages leading to the said discharge passages and said body having four spaced supplemental motive agent passages positioned ninety degrees apart and all in communication with the motive agent supply.
10. A tool for applying coating comprising a body having passages for coating material and for a motive agent under pressure and a member supported for turning movement upon said body and having two opposed supplemental motive agent discharge passages, said member having motive agent passages 47, 48 leading to the said discharge passages and the body having spaced supplemental motive agent passages 50, 51, 52, 53 and an annular passage 49 in communication therewith.
11. A tool for applying coating comprising a body having passages for coating material and for a motive agent under pressure, and a member 42 threaded upon the body; and adapted to be turned thereon into two positions ninety degrees apart in either of which the motive agent may be supplementally discharged, said member 42 when in any intermediate position being thereby prevented from discharging the motive agent supplementally.

In testimony whereof, I have signed my name to this specification.

HERBERT W. DAY.

4. Means for applying coating comprising means to supply coating material, means to subject the same to the action of a motive agent, thereby effecting the discharge of the coating material, and a member through which the motive agent may be discharged supplementally upon the discharged coating material, said member having opposed supplemental discharge passages adapted to occupy discharging positions in two planes or lines which are substantially normal to each other, and to occupy intermediate positions in which the supplemental discharge is prevented by reason of such positioning of said member.
5. Means for applying coating comprising a body having means for maintaining a film of coating material and also having means for causing a motive agent to break through and discharge said film, and a member adapted to discharge the motive agent supplementally upon the discharged film to transform the latter into a mass having a different cross section, said member being mounted for rotation upon said body and adapted supplementally to discharge the motive agent only in a plurality of predeterminedly spaced planes, the control of the discharge of the motive agent supplementally in said planes being effected wholly by change in rotational position of the said member upon said body.
6. Means for applying coating comprising means for maintaining a film of coating material, means for causing a motive agent to break through and discharge said film, and means to discharge the motive agent supplementally upon the discharged film to transform the latter into a mass having a different cross section, the means to discharge the motive agent supplementally upon the discharged film having a plurality of predeterminedly spaced positions in each of which the motive agent is supplementally discharged thereby and intermediate predetermined positions in which no supplemental discharge of the motive agent occurs.
7. A tool for applying coating comprising a body having passages for coating material and for a motive agent under pressure there being in said body a plurality of pairs of spaced, supplemental, motive passages leading from said motive agent passage and distributed in a circular series thereabout and a member supported upon said body and having a pair of opposed supplemental mo-
- tive agent discharge passages, said member having turning movement, without necessary substantial longitudinal movement, upon said body into and out of communication with selected supplemental motive passages.
8. A tool for applying coating comprising a body having passages for coating material and for a motive agent under pressure and a member supported for turning movement upon said body and having two opposed supplemental motive agent discharge passages, said member having two motive agent passages leading to the said discharge passages and said body having a number of spaced supplemental motive agent passages constituting a multiple of two, and respectively in communication with the motive agent supply.
9. A tool for applying coating comprising a body having passages for coating material and for a motive agent under pressure and a member supported for turning movement upon said body and having two opposed supplemental motive agent discharge passages, said member having two motive agent passages leading to the said discharge passages and said body having four spaced supplemental motive agent passages positioned ninety degrees apart and all in communication with the motive agent supply.
10. A tool for applying coating comprising a body having passages for coating material and for a motive agent under pressure and a member supported for turning movement upon said body and having two opposed supplemental motive agent discharge passages, said member having motive agent passages 47, 48 leading to the said discharge passages and the body having spaced supplemental motive agent passages 50, 51, 52, 53 and an annular passage 49 in communication therewith.
11. A tool for applying coating comprising a body having passages for coating material and for a motive agent under pressure, and a member 42 threaded upon the body, and adapted to be turned thereon into two positions ninety degrees apart in either of which the motive agent may be supplementally discharged, said member 42 when in any intermediate position being thereby prevented from discharging the motive agent supplementally.

In testimony whereof, I have signed my name to this specification.

HERBERT W. DAY

Certificate of Correction.

It is hereby certified that the assignee in Letters Patent No. 1,576,725, granted March 16, 1926, upon the application of Herbert W. Day, of Wollaston, Massachusetts, for an improvement in "Apparatus for Applying Coating," was erroneously described and specified as "Painting & Finishing Equipment Sales Co., a Corporation of Massachusetts," whereas said assignee should have been described and specified as *Spray Painting and Finishing Equipment Sales Co., a Corporation of Massachusetts*, as shown by the records of assignments in this office; and that the said Letters Patent should be read with this correction therein that the same may conform to the record of the case in the Patent Office.

Signed and sealed this 20th day of April, A. D. 1926.

[SEAL.]

M. J. MOORE,
Acting Commissioner of Patents.

Certificate of Correction.
